UNITED STATES PATENT OFFICE

2,495,853

SINK AND DRAINBOARD STRUCTURE

Hugo Lindgren, Jamestown, N. Y.

Application February 27, 1946, Serial No. 650,497

2 Claims. (Cl. 4—187)

1

This invention relates to an improved sink and work or drain board structure and more particularly discloses means for joining the meeting or overlapping edges of a sink and drain board in such a manner as to provide a waterproof seal therebetween.

Many different structures have been employed in an effort to create a waterproof seal as between the rim or lip of a sink and the adjoining or enclosing drain board. Presumably, many of these structures accomplish their intended purpose to some extent at least. However, it appears that, in an effort to create a waterproof seal as between a sink and drain board, these prior structures have become increasingly complicated, elaborate and difficult and costly to install.

The structure of the present invention is believed to be such as to provide the desired waterproof seal as between a sink and drain board edges and this, therefore, constitutes one of the objects and advantages.

Another object of the invention lies in the provision of a structure that is readily adaptable to the installation of sinks in work or drain boards, produced in either metal or wood, in such a manner as to provide a waterproof seal between the overlapping parts.

It is considered to be an important object of the invention to provide a waterproof jointure as between sink and drain board that is of simple construction, capable of easy installation, and inexpensive to manufacture.

Other objects and advantages of the invention will be more fully understood from a consideration of the following specification, taken in conjunction with the accompanying drawing; and in which

Fig. 1 is a fragmentary perspective view of a sink and drain board installation embodying one form of the invention;

Fig. 2 is an enlarged vertical fragmentary sectional view, taken substantially on the line 2—2 of Fig. 1, and shows the method of attaching and securing the lip or rim of the sink to the drain board;

Fig. 3 is a fragmentary vertical view, partly in section, taken on the line 3—3 of Fig. 2;

Fig. 4 is a fragmentary vertical view, partly in section, taken on the line 4—4 of Fig. 2;

Fig. 5 is a fragmentary vertical sectional view, taken substantially on the line of Fig. 2, and shows the application of the invention to the installation of a sink or a wood or other thick drain board; and

Fig. 6 is a fragmentary vertical view, partly in section, taken on the line 6—6 of Fig. 5.

Referring more particularly to the drawing, the reference numeral 10 is employed to generally designate a sink and drain board installation in which is embodied one form of the in-

2

vention. In this particular illustration the drain board 11 is formed of sheet metal, and includes a linoleum or other suitable top surfacing material 12. In the illustration of Fig. 1, a sink 13 is mounted in an aperture provided therefor in the metal shelf 11 and material 12. This sink may be of any convenient shape and proportions and includes the conventional, substantially upright walls 14 which, at their upper edges, terminate in an outwardly directed flange or rim 16 connected to the wall by an appropriately curved portion 17. Regardless of any inclination of the walls 14, radius of curve or other design features, the rim flange 16 is in a plane parallel to the plane of the shelf 11.

A number of brackets 18 are permanently joined along their flanges 19 to the under face of the shelf 11. Each of these brackets includes a depending wall 21 that terminates in a flange 22 which projects into the aperture or opening 23 formed by the edges of the shelf and material, 11 and 12 respectively. Permanently joined to the outer face of the wall 14 of the sink are a corresponding number of brackets 24. These brackets are preferably located with their flange 26 extending laterally outwardly from a point adjacent the curved portion 17 of the sink. It will be noted that brackets 18 and 24 are so located that their respective flanges 22 and 26 will be superposed substantially as shown. A suitable opening is made in flange 22 which, when the sink 13 is mounted in the shelf, is adapted to register with a threaded opening in the flange 26. A screw 27 projects through the flange 22 and engages the threaded opening of flange 26. The material 12, adjacent the opening 23, is preferably of lesser thickness to provide a marginal depressed area or ledge 28. The depth of this ledge is equal to, or slightly less than, the thickness of the material of which the flange 16 of the sink is formed.

To assemble the structure embodying the invention, it is found desirable to provide a number of brackets 18 and 24, such as at least four, for the purpose of securing a sink such as indicated in the drawing. When these brackets have been attached, the sink is placed in the opening 23 and screws 27 are mounted, as shown. As the screws are turned down, the flanges 22 and 26 are brought closer together and this action causes the flange 16 of the sink to have such pressure engagement with the somewhat compressible material 12 of the shelf top as to produce a watertight seal as between the material 12 and flange 16.

Referring more particularly to Figs. 5 and 6, it will be noted that a shelf 29, formed from wood or other material of substantial thickness, supports a linoleum or other surfacing material 12, and that this material is formed with a cut down

marginal portion adjacent the sink opening 23, as previously described. The sink 13 and the attached brackets 24 may be similar to that described above. However, the shelf 29 is provided with flat brackets 31 corresponding in number to the brackets 24. Each bracket 31 is secured to the under face of the shelf 29 by one or more screws 32 and is so positioned that an end portion 33 thereof projects into the opening 23 to constitute an equivalent to the flange 22 described above. A screw 34 projects through an opening in bracket 31 into the threaded opening of the flange of bracket 24. This screw, as may be seen, is somewhat longer than the screw 27 and, when turned down, tends to draw flange 26 and bracket 31 together, thus causing flange 16 of the sink to have pressure engagement with the material 12 in a manner to produce a water-tight seal or jointure as between these overlapping parts.

Although applicant has shown and described only two modifications of the invention, it will be apparent to those skilled in the art that further modifications may be made in adapting the invention to other types of sinks or bowls, and that such modifications are contemplated as being part of the invention insofar as they are within the spirit and scope of the annexed claims.

Having thus set forth my invention, what I claim as new and for which I desire protection by Letters Patent is:

1. A structure of the class described comprising a sink having side walls, flanges terminating the edges of said walls, a shelf having an aperture of a size to receive the body portion of said sink, a marginal portion of the edge forming said aperture adapted to be engaged by said flanges, a bracket permanently joined to said shelf and extending into said aperture, another bracket permanently joined to said sink and in spaced super-

posed relationship with said shelf bracket, and means operable to move the sink bracket in a direction to effect pressure engagement of said sink flanges with the marginal portion of said shelf.

2. A structure of the class described comprising a sink having side walls, flanges terminating the edges of said walls, a shelf having an aperture of a size to receive the body portion of said sink, a marginal portion of the edge forming said aperture being adapted to be engaged by said flanges, a bracket permanently joined to the under face of said shelf and extending into said aperture, another bracket permanently joined to one of said sink walls and in spaced superposed relationship with said shelf bracket, the brackets having aligned openings therein, and a screw projected upwardly from beneath said shelf through said openings, said screw having threaded engagement with the walls of the opening in said sink bracket and being operable to draw said sink bracket downwardly to effect pressure engagement of the sink flanges with the marginal portions of said shelf.
